SPLICING DEVICE

Einar Gottfrid Olsson, Oakland, Calif.

Application September 29, 1937, Serial No. 166,456

2 Claims. (Cl. 117—6)

This invention relates to improvements in splicing devices and has particular reference to a needle for use in splicing rope.

The principal object of this invention is to provide a needle which may be inserted through the strands of the rope, through which needle one of the end strands may be passed for the purpose of making a splice wherein one part of the rope passes through and intertwines with another part of the rope.

A further object is to produce a device of this character which is easy to use, economical to manufacture, and readily transportable.

Other objects and advantages will be apparent during the course of the following description.

In the accompanying drawing forming a part of this specification and in which like numerals are employed to designate like parts throughout the same,

Fig. 1 is a side elevation of my needle;

Fig. 2 is a front elevation of Fig. 1;

Fig. 3 is a side elevation of a modified form for use on wire rope;

Fig. 4 is a front elevation of Fig. 3;

Figs. 5, 6, 7, 8, and 9 are illustrative of the manner in which my device is used.

In splicing rope, it is customary to secure either two ends of a rope together or to fold the rope upon itself and intertwine the end strands with the main body of the rope at a point remote from the end. This is usually accomplished by employing a marline-spike, which is merely a tapered pin, the point of which is forced between the strands of a rope to form an opening. Then it is necessary to twist the rope with both hands to hold the opening, after which the marline-spike is withdrawn, and the end of the strand is placed through the opening. This is a very hard and tedious operation, particularly with heavy ropes.

Therefore, I have devised a needle which performs the same function as a marline-spike—namely, the same is forced between the strands, but the same remains in this position during the act of placing one strand through the opening formed by the needle.

In the accompanying drawing wherein for the purpose of illustration is shown a preferred embodiment of my invention, the numeral 5 designates an elongated hollow tube having the end 6 chamfered so as to form a point 7. An opening is shown at 8, which is connected to the chamfered end 6 by a slot 9. An opening 11 is formed near the opposite end from the chamfered end,

which opposite end is interiorly bevelled, as shown in dotted lines at 12.

In the modified form, shown in Figs. 3 and 4, the construction is substantially the same, the only difference being that the same is of smaller diameter, and the end 13 is preferably solid, as with wire ropes, it is necessary to drive the needle through the strands. The parts bearing the same numbers as shown in Figs. 1 and 2 perform similar functions.

In use, the needle is placed through the strand of rope, as shown at A in Fig. 5. Then one of the strands B of the end of the rope is placed through the opened end 6 of the needle until the end of this strand underlies the opening 8. The operator then places the thumb in the opening 8, as shown at C, and withdraws the needle, with the result that the strand B is drawn through the rope, as shown in Fig. 6. Should it be desired to thread the strand B through the rope from right to left, as shown in Fig. 7, instead of from left to right, as shown in Figs. 5 and 6, then the needle is placed through the rope, as shown in Fig. 7, and the strand B is pushed through the opening 8 until it comes out of the end 6, after which the end may be grasped by the hand and pulled. At the same time, the needle may be withdrawn, as shown in Fig. 8, the slot 9 permitting the strand to move from its position through the opening 8, through the slot 9, and out of the end 6. In some instances, it is desirable to lead the strand B through the rope, as indicated in Fig. 9, in which instance, the needle is pushed through the rope until its squared end is almost through the rope. Then the strand B is pushed into the needle, and the finger of the operator is passed through the opening 11 to contact the strand B. This holds the strand in the needle, and by now removing the needle from the rope, the end of the strand will be drawn therethrough. It is, of course, obvious that the other strands pass through the rope in the manner which is customary in making a splice. The squared end of my needle is preferably only used when the strands being operated upon are extremely short.

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I claim:

1. In a splicing needle, a tubular member having an opening therethrough, one end of said

55

needle being chamfered so as to form a point, the other end of said needle being squared with respect to the length of the needle, an opening formed through said needle remote from said pointed end, and a slot connecting said opening and the opening formed by the pointed end.

5 2. A splicing needle comprising a tubular body portion, one end being chamfered so as to form

a pointed opened end, an opening formed in said body portion and spaced from said opened end, a slot connecting said opened end and said opening, a second opening formed remote from said first-mentioned opening and toward the opposite 5 end of said body from said chamfered end.

EINAR GOTTFRID OLSSON.
